SNOW SHOVEL

Samuel E. Allen, Dansville, and Charles L. Kerr,
Pike, N. Y.

Application October 24, 1939, Serial No. 300,980

2 Claims. (Cl. 294—51)

This invention relates to new and useful improvements in implements for removing snow and slush from sidewalks, but more particularly to a snow shovel which may be readily converted for use as a snow pusher, scraper or plow.

It has for one of its objects to provide a convertible snow shovel of this character which is so designed that the relative angle between the shovel-blade and the handle may be easily and quickly adjusted for ordinary shoveling purposes or for effectually pushing or scraping the snow or slush from sidewalks and the like.

Another object of the invention is to provide a snow shovel having simple, strong and durable means for readily adjusting it for adaptation to its different uses.

In the accompanying drawing:

Figure 1 is a perspective view of our convertible shovel showing it adjusted for use as a snow shovel. Figure 2 is an enlarged fragmentary rear view thereof. Figure 3 is a fragmentary side elevation of the implement showing it adjusted for use as a snow pusher or scraper.

Similar characters of reference indicate corresponding parts throughout the several views.

Referring now to the drawing, the numeral 10 indicates the blade of the shovel which is rectangular in plan and slightly curved in cross-section and 11 indicates an adjustable handle which is so joined to the blade as to permit the shovel to be used in the usual way or to so dispose the handle in relation to the blade that the latter will act like a plow or scraper in response to a pushing stroke imparted to the shovel. The upper edge of the blade preferably terminates in a forwardly-facing flange 12, whereby the shovel may be used in an inverted fashion with such flange functioning as a scraping edge for removing ice from sidewalks and driveways.

At its upper rear side and centrally thereof the blade 10 has a channel-like member or frame piece 13 provided with vertically-spaced, transverse pivots 14 and 15. The handle 11 is fitted in the channel member and is pivoted thereto to the pivot 14 so that the handle may be adjusted to a position substantially parallel to the shovel-blade, as seen in Figure 1, in which position the lower portion of the handle is confined against lateral displacement by the side walls of the channel member, or to a position projecting rearwardly from and at substantially right angles to the shovel-blade, as shown in Figure 3. In order to effectually hold the handle in either of its adjusted positions, we provide parallel brace

links 16, 16 which extend along opposite sides of the lower portion of the handle, one end of the links being pivotally joined to the upper pivot 15 of the channel member 13. The other 5 end or remaining portion of each link has a longitudinal slot 17 therein, and the handle is provided with a clamping screw or bolt 18 engaging the link-slots, a wing-nut 19 being provided for securely fastening the links, after 10 setting the handle, in either of its adjustable positions. Near its upper end the channel member 13 is provided with a pair of alining, rearwardly-facing notches 20 with which the clamping bolt 18 is adapted to engage when adjusting 15 the handle to the position shown in Figure 1.

When using the implement as a shovel, the handle is set in the position shown in Figure 1 with the links disposed in parallel relation along opposite sides of the lower portion of the handle 20 and clamped in such position by the bolt 18, the latter being engaged at such time with the notches 20 in the channel member 13. When it is desired to use the implement as a snow 25 plow or scraper, the wing-nut 19 is loosened and the handle 11 swung downwardly to the position shown in Figure 3, thereby moving the links 16 therewith so that they assume an angular bracing position relative to the blade 10. Upon 30 tightening the wing-nut 19, the handle is effectively held in position to enable the implement to be used in the position shown in Figure 3 or, if desired, to be inverted with the flange 12 disposed at the bottom of the blade, whereby the 35 implement may serve as a scraper for effectually removing slush and ice from sidewalks or driveways.

We claim as our invention:

1. A shovel of the character described, comprising a blade having a channel-like frame piece at the upper rear side thereof containing upper and lower pivot elements between the top and bottom edges of said blade, a handle disposed within the channel of the frame piece and connected to said lower pivot element for effecting a relative adjustment of the blade and the handle, an adjustable brace connected at one end to the upper pivot and having a longitudinal slot in its remaining portion, and a clamping screw applied to said handle and having its shank engaging said brace-slot, said frame piece having a notch therein above the upper pivot element for receiving the clamping screw when adjusting the handle to a position substantially parallel to the shovel-blade.

2. A shovel of the character described, com-

prising a blade having a channel-like frame piece at the upper rear side thereof containing upper and lower transverse pivot elements and a rear-wardly-facing notch adjacent the upper pivot element, a handle having its inner end supported in said frame piece against lateral displacement and connected to said lower pivot element for effecting a relative adjustment of the blade and the handle, adjustable brace links disposed in parallel relation along opposite sides of the han- 5 10

dle and connected at one end to said upper pivot, the remaining portions of said links having longitudinal slots therein, and a clamping screw applied to said handle and having its shank engaging said link-slots, said screw being engageable with said frame piece notch in one of the adjusted positions of the handle.
